(57) CLAIM

I claim the ornamental design for the disposable nursing pad, as shown and described.

DESCRIPTION

FIG. 1 is a top view of the disposable nursing pad;
FIG. 2 is a cross sectional view of the disposable nursing pad taken along section lines 2—2' of FIG. 1;
FIG. 3 is a back view of the disposable nursing pad; and,
FIG. 4 is a side view of the disposable nursing pad.
